APPARATUS FOR SEALING CONTAINERS

Harry E. Stover, Long Island City, N. Y., assignor
to Anchor Hocking Glass Corporation, Lan-
caster, Ohio, a corporation of Delaware

Original application August 2, 1940, Serial No.
349,655. Divided and this application June 12,
1941, Serial No. 397,761.

2 Claims. (Cl. 226—88.1)

My invention relates to cap-feeding apparatus. It has to do, more particularly, with apparatus for feeding caps from a source of supply and applying them to containers, such as food containers and including jars, bottles, cans, et cetera, preparatory to sealing them on said containers.

One of the objects of my invention is to provide a simple and effective apparatus for feeding caps from a source of supply into position to be engaged by the upper ends of containers to be sealed thereby which are moved along by a conveyer.

Another object of my invention is to provide apparatus which will automatically release caps from a cap magazine and feed them into position to be engaged by the top of the containers without any manual intervention by the operator.

Another object of my invention is to provide a cap-feeding and applying unit of such a nature that the cap can be withdrawn therefrom by a container on a moving conveyer without danger of upsetting the container.

Another object of my invention is to provide a cap-feeding apparatus of such a nature that the cap which is fed into position to be engaged by a container will not drop from the cap-feeding mechanism until it is positively withdrawn by the passing container.

Another object of my invention is to provide a cap-feeding unit having a magazine for a vertically disposed stack of caps and which is of such a nature that the lowermost cap will be separated from the stack while the stack is supported in position.

Another object of my invention is to provide a cap-feeding apparatus including a magazine and cap-feeding unit which can be removed and replaced readily when different size caps are to be used.

Another object of my invention is to provide a cap-feeding apparatus which is provided with fluid-actuated control and operating mechanism that is positive and efficient.

Another object of my invention is to provide a cap-feeding unit of the type indicated which is readily adjustable for use with containers of varying heights.

In its preferred form, my invention contemplates the provision of a simple apparatus for feeding caps from a source of supply and applying them to containers such as jars, bottles, cans, et cetera. The apparatus is preferably employed with a continuously moving conveyer upon

which the filled containers are placed indiscriminately. Means is preferably provided in association with the conveyer for centering and maintaining containers centered on said conveyer. The containers are first moved by the conveyer to my cap-feeding and applying unit where caps or other closures are loosely positioned on the upper ends of the containers. The containers may then be moved to a sealing unit such as described in my co-pending application, Serial No. 349,655. However, it is to be understood that my cap-feeding apparatus may be used in conjunction with any suitable sealing unit.

15 My cap-feeding and applying unit consists of a magazine for receiving a stack of nested caps. Suitable wedge bars are disposed at the bottom of the magazine for supporting the lowermost cap. When these wedge bars are reciprocated, they separate the lowermost cap from the remainder of the stack of caps and allow it to fall downwardly while still supporting the stack of caps. A support is provided below the magazine for receiving the separated caps and supporting them in position to be engaged and withdrawn by a container moved beneath the cap-feeding and applying unit. For controlling the movement of the wedge bars, I provide a steam controlled cylinder and piston unit. This cylinder and piston unit is actuated by a control trigger adapted to be engaged by a container moved beneath the cap-feeding and applying unit. The steam control and operating mechanism is very simple, positive and efficient.

20 30 35 Various other objects and advantages will be apparent from the following description.

This application is a division of my co-pending application Serial No. 349,655 filed August 2, 1940, Patent No. 2,321,779.

The preferred embodiment of my invention is illustrated in the accompanying drawings, wherein similar characters of reference designate corresponding parts and wherein:

Figure 1 is a side elevational view of a sealing machine having my cap-feeding apparatus associated therewith.

Figure 2 is a plan view of the machine shown in Figure 1.

Figure 3 is a horizontal sectional view showing the cap feeding and applying unit.

Figure 4 is a perspective view of the separating wedges of the cap-feeding unit, showing them in association with each other.

Figure 4a is a perspective view of one of the 45 50 55 wedges.

Figure 5 is a transverse vertical sectional view of one of the wedges showing how it normally supports a cap.

Figure 6 is a transverse vertical sectional view taken substantially along line 6—6 of Figure 2.

Figure 7 is a longitudinal vertical sectional view taken substantially along line 7—7 of Figure 2.

With reference to the drawings, I have illustrated a machine which comprises generally a conveyer unit 1, a cap feeding and applying unit 2 and a sealing head unit 3.

The conveyer unit 1 may be of any suitable type. For example, it may be of the type disclosed in the co-pending application of William D. Bell on Apparatus for sealing containers, Serial No. 314,299, filed January 17, 1940. However, it is to be understood that my apparatus may be associated with any suitable type of conveyer unit. The conveyer unit preferably embodies means for continuously moving the containers into proper association with the units 2 and 3, including means for centering the containers relative to said units.

My invention is not limited to use with any particular type of container and cooperating cap but for illustrative purposes I have shown in Figure 6 a container 4 adapted to receive the cap 5 on its upper end. This cap preferably embodies a substantially disk-like portion 6 (Figure 5) which has a depending annular skirt 7 which carries an annular gasket 8 therewithin. When the cap is forced downwardly onto the upper end of the container, the frictional contact of the gasket with the upper end of the container will aid in maintaining the cap in position and will seal the cap on the container.

The containers 4 are placed indiscriminately on the conveyer and are moved in the direction of the arrows (Figures 1 and 2) by the conveyer. The containers are centered thereon in the manner described in said co-pending application Serial No. 314,299. They are first carried to the cap feeding and applying unit 2. This unit is of such a type that it will apply a cap loosely to the upper end of the container. After the container passes the unit 2, it passes to the sealing head unit 3. This sealing head unit 3 is adapted to displace the air from the head space and to sterilize such space and the cap before the sealing operation.

The units 2 and 3 are disposed directly adjacent each other. They are both supported by a horizontally disposed plate 9. The plate 9 is supported at a point spaced above the conveyer unit 1 by means of four vertically disposed non-rotatable posts 10 two of which are disposed at the left-hand corners of the plate (Figure 1) and the other two of which are spaced a substantial distance from the right-hand end of the plate. Each of these posts 10 is provided with a base portion 11 on its lower end which is suitably secured, as by screw bolts 11a, to a portion of the conveyer unit 1. The upper portion of each of these posts is threaded, as indicated at 12. Each of the posts has an internally threaded worm gear 13 mounted on the threaded portion 12 thereof. Each of these worm gears is disposed directly beneath and engages the plate 9. Formed integral with the left-hand end of plate 9 is a pair of lugs 14 (Figure 2). Formed integral with the plate 9 adjacent its opposite end is a pair of bearing portions 15. The pair of bearing portions 15 rotatably support a horizontally disposed worm shaft 16. The pair of lugs 14 at the

other end of the plate 9 rotatably support a horizontally disposed worm shaft 17. Each of the worm shafts 16 and 17 carries a pair of worms 18 which engage the adjacent worm gears 13. The worm shaft 17 is provided with an angular end 19 for receiving a crank by means of which it may be rotated. In order to rotate the shaft 16 simultaneously with the shaft 17, the shaft 17 is provided on its opposite end with a sprocket 20 keyed thereon. This sprocket has a chain 21 passing therearound which also passes around a sprocket 22 keyed on the corresponding end of the shaft 16.

Thus, it will be apparent that when the shaft 17 is rotated, the shaft 16 will be rotated simultaneously and to the same extent. Consequently, by rotating shaft 17, all of the worm gears 13 will be caused to rotate. Since these gears are threaded on the posts 10, they will be moved vertically on the posts. Furthermore, since the gears are in engagement with lower surfaces of the plate 9, the plate 9 will be moved vertically in accordance with the vertical movement of the gears. Thus, the plate 9 may be adjusted vertically to position the units 2 and 3 at the proper height above the conveyer unit, depending upon the height of the containers to be sealed. It will be noted that all portions of my apparatus are carried by the plate 9. Consequently, it is in the form of a unitary structure which may be readily associated with any suitable type of conveyer unit. The worm and gear units are preferably enclosed in a suitable housing 13a as indicated in Figure 1.

The sealing head unit 3 comprises a vertically disposed cylindrical housing portion 23 which has a base portion that is bolted by means of bolts 24a to the upper surface of the plate 9. The sealing head 26 is vertically reciprocable and embodies a substantially cylindrical portion of non-magnetic metal which is carried on the lower end of a plunger 27 (Figure 7).

The sealing head 26 is provided with a recess 28 in its upper surface which receives the lower end of the plunger 27. The plunger carries an enlarged portion 29 on its lower end which limits its upward movement by contacting with the lower end of housing 23. The plunger 27 is provided with a vertically disposed bore which has an anteriorly threaded lower end that receives the threaded upper portion of a bolt 31. This bolt passes upwardly through a centrally disposed opening 32 in member 26 which is enlarged at its lower end to receive the head 33 of the bolt. The bolt 31 will maintain the head 26 in position on the lower end of the plunger 27.

In order to normally maintain the plunger 27 in its uppermost position I provide the following structure. A pin 35 is carried by the housing portion 23 and extends transversely thereof and through a vertically disposed slot 36 formed in the plunger 27. A compression spring 37 has its lower end resting on this pin 35 and its upper end engaging with the upper end of the bore 30. Thus, this spring 37 normally tends to force the plunger 27 upwardly until the enlarged portion 29 thereof contacts with the lower end of the housing portion 23.

The sealing head 26 is moved by a cylinder and piston unit disposed in housing 59a and connected to member 26 by means including link 52 which is pivoted at 53 to member 27. The housing 59a is mounted on the upper surface of the plate 9 directly adjacent the housing 23. It is provided with a flattened lower surface which

rests on the upper surface of plate 9. A bolt 65 is used to secure the housing 58a to the housing 23.

The cap-feeding and applying unit 2 is illustrated best in Figures 3, 4, 4a, 5, 6 and 7, inclusive. This unit comprises a plate 133 which is suitably mounted on the plate 9 over a large opening 25a (Figure 2) in the plate 9. This plate 133 has a portion 134 which extends down into the opening 25a. The plate 133 is held in position on plate 9 by means of pins 135 extending into openings formed therein so that it may be readily removed. The plate 133 is provided with a centrally disposed opening 136 which is in alignment with the sealing head 26. This opening 136 is of the proper size to permit the caps, to be applied to the containers, to drop freely therethrough. The plate 133 carries four upstanding posts 137 which are spaced circumferentially around the opening 136. These posts 137 are adapted to receive a stack of the nested caps. The plate 133 has a plate 133a bolted by means of bolts 133b to the lower surface thereof. Plate 133a has an opening corresponding with opening 136.

For controlling the feed of the caps downwardly through the opening 136, I provide the following structure. This structure embodies a pair of cap separating wedge members 138. These wedge members 138 are disposed tangentially to the opening 136, as indicated best in Figure 3. They are mounted for longitudinal movement in recesses 138a formed in the lower surface of the plate 133. The recesses 138a extend substantially tangential to opening 136 and are in communication therewith at their inner edges. The lower wall of these recesses is formed by plate 133a. The members 138 are connected together at one end by a bar 139. The other ends of members 138 engage a bar 140. The bar 140 carries a pin 141 (Figure 6) which is mounted for axial movement in a bearing portion 9a formed on plate 9. A small plate 143 is attached to the lower surface of portion 9a and extends beneath bar 140. This plate carries a pin 144 on its inner end to which one end of a spring 145 is attached. The other end of the spring 145 is connected to a depending pin 141a carried on the outer end of pin 141. The spring 145 will tend to pull the bar 140 to the right, holding the bar in contact with the ends of members 138. This will also hold the bar 139 in contact with the outer end of piston rod 146. The piston rod 146 is carried by a piston 146a disposed in a cylinder 147 carried by the plate 9. The piston 146a is provided with a projection 146b on its outer end which engages the end of cylinder 147 to keep the piston spaced therefrom. The piston 146a is normally held in the position indicated in Figure 6. It will be apparent that when the piston is reciprocated, the members 138 will also be reciprocated.

The members 138 are of the shape shown best in Figures 4 and 4a. Each of the members 138 is notched intermediate its ends to provide a recessed flat vertical surface 151. This surface has a cap-supporting shelf 155 formed adjacent one end thereof and a cap-separating wedge portion 158 projecting inwardly past said surface adjacent the opposite end thereof. The portion 155 has a knife edge 156 formed thereon.

The wedge portion 158 is provided with a horizontally disposed upper edge 160 which is spaced above the top surface of portion 155 a distance substantially equal to the thickness of a cap. 75

The lower edge 161 of wedge portion 158 is inclined so that the end 159 of portion 158 is pointed. The points 156 and 159 are spaced apart. The members 138 are normally in such a position that the lowermost cap will be supported by the projecting portions 155 of the members 138 which will project into opening 136. However, when the members 138 are moved to the left (Figure 6) by outward movement of the piston 146a, this causes the portions 155 thereof to be withdrawn from the opening 136, permitting the lowermost cap to drop from the opening. At the same time that the portions 155 are withdrawn, the pointed ends 159 of the cam portions 158, which are normally out of opening 136, are projected into opening 136 and pass between the lowermost cap and cap next above.

The wedge-shaped portions 158 actually serve to force the lowermost cap downwardly. It is desirable to have this positive action rather than to rely upon gravity, because the caps may tend to stick together. The straight upper edges 160 of the portions 158 will support the cap next above and the entire stack during the time portions 155 are in withdrawn position. As soon as the members 138 are returned to their original positions, the portions 155 will again project into the opening 136 and the lowermost cap will rest thereon, since the wedge portions 158 have been moved from beneath the cap which they were previously supporting and have been withdrawn from opening 136. Thus, it will be apparent that each time the members 138 are moved to the left (Figure 6) a single cap will drop through the opening 136.

It will be apparent that the unit, consisting of plate 133, posts 137, carried by such plate, and members 138, mounted for longitudinal movement in guides in said plate, together with bar 139, can be readily removed and be replaced with a similar unit for different size caps. The removal of this unit is facilitated because piston rod 146 and member 140 are not mechanically connected thereto.

The cap released from the stack will drop downwardly onto a tongue member 162 which is secured to member 133a. The tongue member 162 extends beneath the opening 136. It is held in position by means of a pin 162a which extends through an opening in a vertical extension of member 162 and into an opening in member 133a. The pin 162a is split so that it will be held in the opening by friction and is formed in the inner end of a handle 162b. The tongue may be readily removed to permit removal of the unit, carried by plate 133.

Disposed beneath plate 133a and bolted thereto is a pair of parallel tracks 165 (Figures 3 and 7) which extend forwardly towards the sealing head 26. These tracks 165 are spaced apart a proper distance so that they will support the cap 5 released from the stack. Thus, the cap will be supported in an inclined position, as indicated in Figure 7, by the tracks 165 engaging it at diametrically opposed points and by the tongue member 162 engaging the rear edge thereof. Although the members 165 are spaced a distance such that the cap will rest thereon, they are spaced sufficiently to permit the upper end of the container to pass therebetween, it being understood that the cap is slightly greater in diameter than the upper end of the container.

It will be apparent that all parts of the cap feeding unit are carried by the plate 133. Consequently when different sized caps are used, the

entire unit may be removed easily and quickly and replaced with a different unit adapted to contain and feed caps of a different size. When removing the cap feeding unit, the pin 162a may be removed by withdrawing handle 162b to permit the removal of tongue 162 so that the cap feeding unit may be lifted out of position.

When the conveyer moves a container beneath the cap feeding unit 2, the upper end of the container will engage the skirt of the inclined cap disposed in the position indicated in Figure 7. This will move the cap along the tracks 165 with the container, and onto tracks 165a which extend to a point adjacent the sealing head 26 (Figure 3). The tracks 165a are supported in a manner to be explained later. The cap and container will be moved along until they pass beneath the sealing head 26 where the sealing will take place in the manner described in my co-pending application.

The tracks 165a are supported in the manner illustrated best in Figure 3. They are bolted, as at 165b, to the ends of the members 171 associated with the sealing mechanism. A bolt 165c extends transversely of the tracks and connects them together to prevent spreading thereof. As described in my co-pending application, members 165a are adjustable towards or away from each other with members 171. During this adjustment the bolt 165c must be disconnected and after the adjustment, it may be replaced.

In order to supply steam to the cylinder 147 to actuate the cap feeding unit, I provide means which is actuated by movement of the container into a position below the cap feeding and applying unit. As illustrated best in Figures 3, 6 and 7, this means comprises a small roller 186 which is held in a fixed position on the lower side of plate 133a. This member 186 is located directly below the opening 198 substantially in alignment with the piston rod 146, as illustrated best in Figure 3. At a diametrically opposed point a washer member 187 is disposed on the plate 133a. A small pin 188 prevents complete removal of the washer but it is free to move to a considerable extent. A plunger 189 normally engages the washer 187 and holds it in its outermost position.

The plunger 189, as shown best in Figure 6, is disposed for reciprocation in a bore 190 formed in a valve housing 191 mounted on the cylinder 147. The plunger is provided with a reduced portion with which the inner end of a set screw 192 cooperates to permit limited movement of the plunger but to prevent complete withdrawal thereof. The plunger is normally held in its outermost position by means of a spring 193. The bore 190 communicates with a passageway 194 which leads into the left hand end of cylinder 147. This end of the cylinder is provided with an exhaust outlet 195. A second passageway 196 communicates with the bore 190. The end 197 of this passageway is normally uncovered by the plunger 189. This passageway 196 communicates with a chamber 199 in which a piston valve 200 is disposed for reciprocation. This piston valve 200 is reduced to form an annular chamber 201. The annular chamber 201 is in communication with the passageway 196 by means of a small bore 202 formed in piston valve 200. The chamber 201 is also always in communication with a steam inlet 203 which is connected to a steam conduit 204. The opening 147a at the right hand end of the cylinder 147 communicates with the bore 190 through the medium of an opening 205 in member 191. The valve 200 is normally held in the

position indicated in Figure 6 by means of a spring 206, the force of which is adjustable by means of a screw 207. The opening 205 is normally uncovered by the piston valve 200 and is in communication with an exhaust opening 208.

With the parts in the position illustrated in Figure 6, steam will flow from the line 204 through annular chamber 201, through the bore 202, passage 196 and through the exhaust outlet 195. The passageway 202 is small so that a small amount of steam only will normally escape and this will serve to keep the steam alive. As soon as a container is brought by the conveyer beneath the cap feeding and applying unit 2, the upper end of it will engage the roller 186 and the washer 187. This will happen substantially at the same instant that the forward edge of the container engages the inclined cap and tends to withdraw it from its inclined position on the tongue 162. Engagement of the upper end of the container with the washer 187 will force it outwardly, it being understood that the inner edge of the washer and the inner edge of the roller 186 are normally spaced apart a distance slightly less than the diameter of the upper end of the container.

Outward movement of the washer 187, will move the plunger 189 to the right closing the upper end 197 of the passageway 196. This will cause steam pressure to build up within the passage 196, forcing the piston valve 200 to the right.

The piston valve will be moved to such a position that the exhaust opening 208 will be covered while the chamber 201 will be in communication with the opening 203. This will permit steam to flow into the right hand end of cylinder 147 and will force the piston 146a to the left, actuating the cap feed to drop another cap into the position indicated in Figure 7, it being understood that the cap previously in this position has been withdrawn and moved along by the container which engaged the washer 187. There will be a delayed action of the piston valve 200 until pressure in passage 196 builds up which will prevent interference of the cap dropped with the cap previously in such position. After the container moves beyond the washer 187, the plunger 189 will be returned to its original position by spring 193. This will expose the end 197 of the passageway 196, and will permit the steam to escape from passage 196 through passage 194. The reduction in pressure in the passage 196 will permit the piston valve 200 to be returned by the spring 206 to its original position. Then steam can escape from the right hand end of cylinder 147, through opening 147a and 205, through bore 190 and through the exhaust opening 208. This will permit the spring 145 to return the piston 146a to the position indicated in Figure 6. Thus, each time a container moves beneath the cap feeding unit and withdraws and moves along the cap supported by the tongue 162 and tracks 165, it will actuate the cap feed to drop another cap into such position.

As illustrated best in Figures 1 and 6, the line 204 for supplying steam to the cylinder 147 extends into a housing 210 mounted on the plate 8. The line 81 which supplies steam to the unit 59, for actuating the sealing head, also extends into housing 210. A steam pressure regulating valve 211 of a suitable type is also provided. A steam pressure gage 213 is also provided and will indicate the pressure of the steam flowing to the unit 59 and the cylinder 147.

From the preceding description, the operation

of the entire machine will be well understood. The conveyer will be continuously driven and the plate 9 will be adjusted to the proper height above the conveyer depending upon the height of the containers to be sealed. The cap feeding unit will be of a suitable type to handle caps of the correct size to be applied to the containers. The containers will be placed indiscriminately on the conveyer and will be moved beneath the units 2 and 3. As a container is moved beneath the unit 2, it will withdraw a cap from said unit in the manner previously described. The container with a cap loosely thereon will then be moved beneath the sealing head 26 where sealing will take place as described in my copending application.

It will be apparent from the above description that I have provided a cap-feeding and applying unit having many advantages. The unit will serve to feed caps from a source of supply into position to be engaged by the upper end of containers to be sealed thereby and which are moved along by a conveyer. The cap-feeding operation is entirely automatic. The caps can be withdrawn from the unit by a container on a moving conveyer without danger of upsetting the container. However, the cap must be positively withdrawn by the container. The cap-feeding unit can be replaced readily with units for different sized caps and it may be adjusted vertically for different sized containers. The steam-operated control mechanism of the cap-feeding unit is very positive and efficient.

Various other advantages will be apparent from the preceding description, the drawings and the following claims.

Having thus described my invention, what I claim is:

1. In combination with a movable conveyer for supporting a plurality of containers and a unit adapted to be operated when a container is moved into association therewith, a control system for operating said unit, said control system including a fluid-actuated power unit, a main control valve for controlling the supply of fluid to said power unit, a pilot valve for controlling the supply of fluid to said control valve, and means for moving said pilot valve to actuate said main valve, said means comprising a trigger movably mounted, and a stop member spaced therefrom, said trigger and said stop member being associated with the conveyer so that the containers will successively pass therebetween and normally being spaced apart a distance less than the transverse dimension of the containers.
2. The structure set forth in claim 1 wherein the pilot valve is held in normal position by a spring, and wherein the trigger comprises a horizontally disposed washer engaging said pilot valve and being mounted for bodily movement in a horizontal plane and the stop member comprises a roller mounted for rotation about a fixed axis in a horizontal plane.

HARRY E. STOVER.
